Application May 4, 1959, Serial No. 55,756

Term of patent 14 years

(Cl. D48—23)

FIG.2

FIG.3

FIG.4

Figure 1 is a perspective view of a lighting fixture showing my new design;

Figure 2 is a top plan view thereof;

Figure 3 is a view in side elevation thereof;

Figure 4 is an elevational view thereof taken from the opposite end of Figure 1; and

Figure 5 is an enlarged fragmentary section taken along line 5—5 of Figure 1.

The oval-shaped members on the sides of the lighting fixture on the drawings are shaded to indicate color contrast.

I claim:

The ornamental design for a lighting fixture, as shown and described.
